UNITED STATES PATENT OFFICE

NICHOLAS J. VERRET, OF MEMPHIS, TENNESSEE

TAKE-OFF AND LANDING APPARATUS FOR AEROPLANES

Application filed September 18, 1928. Serial No. 306,635.

My invention relates to the operation of aeroplanes, and the main object in view is the provision of an apparatus by means of which an aeroplane can safely take off and land in a comparatively small space so as to avoid the necessity of a large field as now used.

A further object of my invention is to provide an apparatus occupying comparatively small space for starting an aeroplane in its flight and catching the same in landing and which will also provide for safely teaching the art of flying as well as provide a means for encouraging those to use an aeroplane who may be timid in undertaking a regular trip, the apparatus carrying the aeroplane through the air at any speed and from which it may or may not be released according to the will of the operator or the wishes of the passenger or passengers.

With these principal objects in view my invention contemplates an apparatus in which the aeroplane is started on its flight and caught in landing by means of an arm or beam revolving in a horizontal plane on a tower, with depending loops at the outer ends of said arm or beam with which a hook on the aeroplane engages in landing, together with a cable suspended from the cross arm for supporting the aeroplane until said arm revolves at the proper speed which will insure the onward flight of the aeroplane when released, the tower and revolving cross arm supported thereby being preferably so constructed as to provide an observation tower and moving walkway or promenade for the amusement and pleasure of the general public without in any way affecting its usefulness with regard to the main purpose of starting and landing aeroplanes in a comparatively small area.

With this general statement of the purposes of my invention and the manner in which they are accomplished it will be understood that the drawings and following description set forth certain forms in which my invention may be embodied, and that further modifications or changes may be made in the general plan to attain the same ends, all within the spirit and scope of the appended claims.

In the drawings—

Figure 1 is an elevation showing the preferred form of my invention.

Fig. 2 is a plan view thereof, parts being broken away.

Fig. 3 is a detail view showing the means for revolving the cross arm.

Fig. 4 is a similar view of the means for operating the raising and lowering cable.

Fig. 5 is an elevation showing a modification in the general construction of the apparatus.

Fig. 5^a is a small diagrammatic view of a modification of Fig. 5.

Fig. 6 is a plan view of Fig. 5, with parts broken away.

Fig. 7 is a detail view of means for operating the driving propellers of the cross arm.

Fig. 8 is an enlarged detail view of the aeroplane carrier at one end of the cross arm.

Fig. 9 is a plan view thereof.

Fig. 10 is a vertical sectional view through the aeroplane carrier on the line 10—10 of Fig. 8.

Fig. 11 is a view to illustrate the catcher hook which is carried by the aeroplane.

Fig. 12 is a detail view of the suspending and releasing means carried by the aeroplane; and

Fig. 12^a is a detail view of the chain forming part of the suspending and releasing means.

Carrying out my invention in the form of apparatus shown in Fig. 1 I provide a tower A comprising a steel frame having uprights 14 rising from a concrete base 15 and supporting an elevated cabin 16 of circular shape on which at the outer edge thereof are two sets of circular tracks 17 17 over which travel flanged traction wheels 18 18 (Fig. 3) for rotatably supporting a cross arm or horizontal beam 19 projecting beyond opposite sides of said cabin for a considerable distance, the said arm being centered by a vertical shaft or mast 20 stepped in a socket 21 on a platform 22 at a suitable distance below the cabin through which latter said shaft extends to a height for connecting guy ropes or cables 23 to the upper end thereof for which purpose a casting 24 is mounted on said upper

end of the shaft. Access to the cabin from the ground is by means of an elevator or shaft 25 it being understood that the cabin is stationary while the cross arm revolves thereon, and in order to reach the cross arm from the cabin there is a stairway 26 (Fig. 2) leading from one to the other. The cross arm is constructed of steel beams upon which is laid a flooring 27 to form a walkway or promenade protected at its opposite sides by railings 28 with the usual balusters or palings, and in order to support the electric motors 29 which drive the traction wheels 18 bays or platforms 30 are provided at opposite sides of the walkway and located above the circular tracks for convenience in connecting the motors thereto through the intervention of gear-wheels 31 and 32, the shaft 33 from the motor and supporting the gear wheel 31 being mounted in bearings 34, while the shaft 34^a carrying the gearwheel 32 as well as the traction wheels is mounted in bearings 35, said bearings and brackets being secured to the upper and lower sides of the bay or platform as shown in Fig. 3, and it will be understood that this arrangement is duplicated at the other side of the walkway or promenade and at the opposite side of the cabin as shown in Fig. 2. For the purpose of catching and supporting an aeroplane at either or both ends of the cross arm I provide a special form of device which is more clearly illustrated in Figs. 8, 9, and 10 of the drawings, and for supporting this device the outer ends of the steel beams forming the main part of the arm are extended upwardly and outwardly to receive between them a rectangular metal frame 36 having outwardly extending parallel arms 37 37 connected to the outer ends of said beams by a crossbar 38 and spaced apart for the depending member 39 pivoted at its upper end on said cross bar and bifurcated at its lower end to present diverging arms 39^a 39^a between the lower ends of which is a downwardly curved rod or loop 40 on which the aeroplane is caught. The depending member or aeroplane catcher 39 is reinforced against longitudinal movement—in the direction in which the cross arm moves—by means of plates 41 curved in the arc of the circle the center of which is the crossbar 38 and connected at their ends between the parallel arms 37, said arcuate plates being separated or spaced apart to permit movement of the aforesaid depending member or aeroplane catcher and carrier between them. The depending member or carrier is provided with rollers 42 at opposite sides thereof which bear on the upper edge of the auxiliary supporting plates, and it will be noted that this member or loop has a swinging movement outward to accommodate the outward thrust of the aeroplane caused by centrifugal force as the cross arm rotates at a

rapid rate of speed. For raising and lowering the aeroplane to and from the catcher-loop or carrier 39 I provide a cable 43 wound on a drum 44 (Fig. 4) supported in bearings 45 and operated by an electric motor 46 on a platform 47 resting on and between the rails 28 adjoining said catcher and carrier, said motor being geared to the drum by shaft 48 and intermeshing gear wheels 49 and 50. The cable is provided with a ring 51 at its lower end for connecting the same in any suitable manner to the aeroplane, as for instance by means of the catcher hook shown in Fig. 11 and hereinafter particularly described. Although I have shown electric motors for driving the traction wheels it will be understood that any other form of power may be used, and it will be also understood that the electric motors are connected to a suitable source of electric supply and the operation of the same as well as their speed controlled in the usual manner by a controller (not shown) located in the cabin or at the motors.

I prefer that the aeroplane be provided with a catcher hook such as illustrated in Fig. 11 consisting of a flat bar of metal 52 loosely connected to the outer end of the propeller shaft 53 and presenting a vertical member extending downwardly and upwardly in front of the propeller to protect the same with the rearwardly curved member above the propeller bent in the form of a hook 54 thoroughly braced by tie rods 55 and 56 extending from the horizontal portion of said catcher-hook to the fuselage. The bill 54^a of the hook is of a particular formation so that it will receive the curved rod or catcher-loop 40 of the aeroplane carrier 39 at the outer end of the cross arm of the apparatus hereinbefore described and be suspended from said catcher-loop as the arm is slowed down after the aeroplane is properly caught, the inner end of the hook being located with respect to the aeroplane so that the latter will be properly balanced when both the aeroplane and cross arm come to rest. This catcher-hook may also provide for launching the aeroplane after it is speeded up faster than the arm carries it around in starting said aeroplane on its flight, for instance by providing the upper or bill end of the hook with a small auxiliary hook 57 turned in the opposite direction from the main hook hereinbefore referred to; in other words this auxiliary hook will hold the aeroplane by reason of the loop 40 engaging in the same as soon as said loop is held in the closed end of said auxiliary hook but the latter will freely leave the hook when the speed of the aeroplane exceeds the speed of the arm as will be readily understood. As another means of suspending the aeroplane from the arm either in launching the same or when it is desired to keep it moored to the arm the raising and lowering cable may be employed,

in this instance in connection with the device illustrated in Figs. 12 and 12^a consisting of a chain 58 with a hook 59 adapted to engage in the eye 51 on said suspending cable, and for detachably connecting the chain to the aeroplane it is provided with an eye 60 engaging a clevis 61 and removable pin 62 suitably located on the fuselage as for instance in the rear of the cockpit so that the pilot may readily disconnect said chain.

In the operation of the apparatus hereinbefore particularly described an aeroplane may be launched either from the catcher-loop 40 by means of the catcher-hook 54 on the aeroplane, or by means of the raising and lowering cable 43 in connection with the releasing device on the aeroplane consisting of chain 58 and clevis 61 in either instance after the arm is speeded up so that the aeroplane will be supported by the wings for taking off in flight it will either automatically leave the arm, when connected to the catcher-loop by the auxiliary hook, or released by withdrawing pin 62. In landing the aeroplane first circles the arm and when it approximates the speed of said arm it travels until the catcher-hook thereon is in the same horizontal plane as the catcher-loop, being then speeded up to engage the catcher-loop and be supported from the arm as the latter is brought to rest, when said aeroplane may be lowered by means of the cable 43 operated by the electric motor 46. From this it will be obvious that the apparatus provides a simple and effective means for starting an aeroplane in its flight and for landing the same, and as the apparatus occupies a small area as compared with take-off and landing fields ordinarily used, it can be located in restricted areas or districts with reference to cities. Furthermore, as the arrangement provides for mooring the aeroplane to the end of the arm passengers can experience all the sensation of flying without danger of clashing which will not only be helpful to those too timid to risk a regular flight but also of special service to those learning to manipulate the controls of aeroplanes, in both instances the speed being regulated whereby in the case of a student he can detach the aeroplane from the loop when he has the required confidence to operate the aeroplane in flight, by speeding the arm to the extent of starting him on the flight. It will be noted also that the particular construction of the apparatus as shown in Fig. 1 provides in addition to its usefulness in launching and landing aeroplanes a form of amusement or pleasure by persons riding in the revolving cabin or on the cross arm, in the latter instance the speed of travel of the person on the cross arm being increased the further he goes from the center of said arm. With respect to the feature of the apparatus with regard to the amusement or pleasure of persons riding in the cabin or on the arm it may be stated

that they are located at approximately fifty feet from the ground, and that the arms are each from ninety to one hundred feet in length so that the speed of the outer ends of the arm is considerably greater than the speed at the center, at which latter point it is comparatively slow permitting the use of the stairway 26 in reaching the promenade or walkway, the length of the arm also provides that the outer ends thereof being approximately two hundred feet from each other there is no likelihood of the aeroplane trailing one arm being overtaken by the other.

A lighter construction of apparatus is shown in Fig. 5 of the drawings in which the tower B mounted on the concrete base 65 has a circular platform 66 at its upper end on which is mounted a turntable 67 carrying the cross arm 68 centered by mast 69 to the upper end of which latter guy ropes or cables 70 are connected and in this instance the arm may be revolved by means of propellers 71 driven by electric motors 72 connected thereto by belt 73 (Fig. 7), the driving shaft 74 carrying pulley 75 being geared to the motor shaft 76 by intermeshing gears 77 and 78. However, the driving mechanism hereinbefore described with reference to Fig. 1 may be employed, as will be obvious. In this form of the apparatus one end of the arm is shown provided with an aeroplane carrier, such as hereinbefore described and having catcher-loop 40, and the other end provided with a projecting bar 79 by which the aeroplane may be suspended and from which it may be automatically launched when the cross arm attains sufficient speed to discharge the aeroplane by centrifugal force. With the exception of this arm and location of the raising and lowering cable 80 a distance from the outer end of the arm the operation of this form of the apparatus in starting aeroplanes and launching the same is the same as that heretofore described, but with this lighter structure the cabin, as well as the walkway or promenade are dispensed with, and access to the beam is by way of a ladder 81. This lighter form of construction is desirable in providing an apparatus for use in instructing persons desiring to learn the operation of flying aeroplanes, although it will be found also serviceable for the simple operation of starting and landing aeroplanes. For the purpose of directing aeroplanes in flight to the landing apparatus a cluster of lights 82 is mounted on the mast, to throw the light upward and thereby not interfere with the operation of the pilot catching his aeroplane on the catcher-loop, and for the further convenience of the pilot in landing at night green lights may be placed at opposite sides of the aeroplane catcher or carrier at each end of the arm. In this instance the construction of the apparatus may be further lightened by providing a single arm on tower C, as illustrated in the

diagrammatic view Fig. 5^a, the weight of the arm and that of the aeroplane to be suspended at the outer end thereof being overbalanced by a weight w .

It will be understood of course that the apparatus hereinbefore described is not only adapted to be placed on the ground but may be also mounted on the deck of a vessel, either a passenger vessel or warship, but in this latter instance the form of device or apparatus illustrated in Fig. 5 would be more suitable in that the construction thereof is lighter than that shown in Fig. 1 of the drawings.

I claim:

15. 1. In combination with a cross arm revolving in a horizontal plane and having a catcher-loop at the outer end thereof, of a hook mounted on the outer end of the propeller shaft of an aeroplane, said hook being bent over the upper end of the propeller of the aeroplane and extended rearwardly therefrom and terminating in a hook with the bill projecting forwardly.
20. 2. In combination with a cross arm revolving in a horizontal plane and having a catcher-loop at the outer end thereof, of a hook mounted on the outer end of the propeller shaft of an aeroplane, said hook being bent over the upper end of the propeller of the aeroplane and extended rearwardly therefrom and terminating in a hook with the bill projecting forwardly and rearwardly to form an auxiliary hook, in which the main hook opens forwardly and the auxiliary hook rearwardly.
25. 3. In combination with a cross arm revolving in a horizontal plane and having a catcher-loop at the outer end thereof, of a hook mounted on the outer end of the propeller shaft of an aeroplane and bent rearwardly over the propeller with said hook opening out forwardly, and rods bracing the rearwardly projecting portion of the hook to the fuselage.
30. 4. In combination with a cross arm revolving in a horizontal plane and having a catcher-loop at the outer end thereof, of a hook mounted on the outer end of the propeller shaft of an aeroplane and having a vertical portion extending downwardly and upwardly from said shaft with the open end of the hook at the forward end thereof.
35. 5. In combination with a cross arm revolving in a horizontal plane and having a catcher-loop at the outer end thereof, and a raising and lowering cable extending from a drum mounted on the arm and having a ring at its lower end, of a flexible connection carried by the aeroplane, a clevis and removable pin connection said flexible connection to said aeroplane, and a hook mounted on the outer end of the propeller shaft to extend over the propeller and terminate in a hook opening out forwardly.

NICHOLAS J. VERRET.
